John White

Daniel Dayton Flream Scott, and John White
Petters Patent

The schedule referred to in these Petters Patent and making part of the same containing a description in the words of the said Daniel Dayton Flream Scott and John White themselves of their improvement in making and constructing coffins from the American or hydraulic cement.

Specification of the invention or improvement in making and constructing coffins from the American or hydraulic cement. The form of the coffin is first made with common boards of the desired shape and about an inch less than the desired dimensions as to the sides and ends and planed smooth and ^{so} gradually to be put up or to here down. The cement is made of the consistency of common mortar. The cement is first laid on a board to the a thickness ~~of~~ or otherwise from one half an inch to three inches in thickness and of a corresponding thickness all round wider and larger than the form. The form is then placed on the cement bottom. The cement is then put on the sides and ends of the form of a thickness corresponding with the bottom all round and even with the top of the form well finished or smoothed with a bowell or otherwise. On the coffin may be formed by placing the cement in the manner above specified on the inside of the form made from one half an inch to three inches larger than the desired dimensions or it may be formed by first constructing two forms with common boards one less than the desired dimensions about one inch and the other from one half an inch to three inches larger than the first then lay the cement upon the bottom of the outer form then place the inner form or mold upon the cement bottom and fill in the cement between the form packed back and even with the tops of the form. and if necessary and in order to prevent the last adhesion of the cement to the forms. first coat them with a thin layer of moistened clay or other materials. And in either case after the cement has become set it is taken out of off by removing the form in parts. The lid which is made whole or for convenience in separate parts is formed on a separate mold.

should or moles to coincide and in size and thickness to that of the main part of the coffin or to project over the top of the same about one inch, a groove may be formed in the lid to fit the tongue on top of the coffin, or the lid may be so constructed that one half of the thickness shall fit within the body of the coffin and the other project over the top of the same. To secure the top bolts or pins may be if necessary inserted into the sides of the coffin while the cement is yet soft and holes made in the top or lid to receive the bolts or pins and to be firmly secured with nuts and screws. And when put on for interment the joints around the top should be filled with the same or otherwise cement, should it be desired a piece of thick glass may be placed in the lid for the purpose of seeing into the coffin, and made permanent, by being let into the surrounding cement. Should it be desired the coffin may be faced either externally or internally with wood, rosy, rich lead or any other metallic substance. Such coffins will soon become firm and durable and impervious to air or water and may be put into the earth or vaults and the remains of the deceased may thereby be preserved entire for years. This improvement or invention consists in making coffins of the American or Hydraulic cement and that improvement or invention only is hereby desired to be patented. In testimony whereof that the foregoing is a true specification of our improvement above described we have hereunto set our hands and seals this twenty-seventh day of January A.D. 1835.
